UNITED STATES PATENT OFFICE.

JESSE WALRATH, OF RACINE, WISCONSIN.

CONTROLLING-VALVE FOR EXPLOSIVE-ENGINES.

SPECIFICATION forming part of Letters Patent No. 688,908, dated December 17, 1901.

Application filed October 12, 1900. Serial No. 32,879. (No model.)

To all whom it may concern:

Be it known that I, JESSE WALRATH, a citizen of the United States, residing at Racine, in the county of Racine and State of Wisconsin, have invented certain new and useful Improvements in Controlling-Valves for Explosive-Engines; and I do hereby declare the following to be a full, clear, and exact description of the invention, such as will enable others skilled in the art to which it appertains to make and use the same.

My invention is an improvement in adjustable controlling-valves for explosive-engines; and it consists in the novel features hereinabove described, reference being had to the accompanying drawings, which illustrate one form in which I have contemplated embodying my invention, and said invention is fully disclosed in the following description and claims.

Referring to the drawings, Figure 1 represents a vertical sectional view of a controlling-valve embodying my invention. Fig. 2 represents a cross-section on line 2 2 of Fig. 1. Fig. 3 represents a cross-section on line 3 3 of Fig. 1. Fig. 4 represents a cross-section on line 4 4 of Fig. 1. Fig. 5 represents a plan view of the bottom plate and split clamping-ring.

The object of my invention is to provide a valve in which the ports for admitting gas (or vapor) and air can be adjusted without the possibility of altering the relation between the areas of the gas-inlet ports and the air-inlet ports and without interfering with the operation of the valve under the influence of the governor.

In the drawings I have shown the upper part of the valve-casing constructed to supply two cylinders with explosive mixture, and a valve is shown for controlling the admission of the mixture to one or both cylinders; but this construction is not an essential part of my present invention, as my improved valve may be used with equal advantage with one or more cylinders.

In the drawings, A represents the valve-casing, which is provided, preferably, with three internal chambers—a mixing-chamber a , an air-chamber a' , communicating at a^3 with the atmosphere, (or with an air-supply,) and a gas or vapor chamber a^2 , communicating with a supply of gas or vapor, as at a^4 .

The casing A is closed at its upper end by a plate B, having a central bearing-aperture b , in which is mounted the vertical stem c of a cut-off valve C, which is preferably in the form of a cylinder open at its lower end and provided at its upper end with a central stem c , above referred to. The cylindrical wall of the valve C is provided in this instance with two apertures $c' c^2$, adapted to register with two inlet-passages $A' A^2$, formed in the casing A and adapted to be connected with the two cylinders of an explosive-engine. The stem c of the valve C is provided with a hand-lever c^3 , having a handle c^4 and an indicator c^5 , so that the operator can tell in what position the valve is set and can readily move it into position to open communication with either or both of the passages $A' A^2$.

A tubular inner casing or lining D is inserted into the lower end of the outer casing A and has an enlarged upper cylindrical portion d , adapted to fit circular openings a^5 and a^6 above and below the air-chamber a' . The lining D is also provided with a cylindrical part d' below the part d , which is of less diameter than part d and extends through the gas or vapor chamber a^2 , and terminates at its lower end with a horizontal plate d^2 , which fits over the lower end of casing A and is designed to be secured thereto by screws, as hereinafter described.

E represents a vertically-movable and laterally-adjustable tubular valve which extends up through the part d' of the lining D (in which it fits easily) and to the top of lining D. The upper part of the valve E is provided within the part d of the lining with radially-disposed webs e , which carry a cylindrical portion e' , fitting and working in the upper part d of the lining D. The upper part d of the lining is provided with a plurality of horizontally-disposed slots d^3 for the purpose of admitting air, and the cylindrical part e' of the valve E is provided with similar apertures e^2 , adapted to register with the apertures d^3 . (See Figs. 1 and 3.) The part d' of the lining D is provided with a series of gas-inlet slots d^4 , and the tubular portion of the valve E is provided with slots e^3 , which are adapted to register with the slots d^4 , as shown in Figs. 1 and 4. The combined areas of the air-inlet apertures d^3 bear a definite

predetermined relation to the combined areas of the gas-inlet apertures d^4 , and I have found by experiment that the ratio between the two may be fixed at eight to one (8 to 1) with advantageous results, or, in other words, the combined areas of the air-inlet apertures are eight times as great as the combined areas of the gas-inlet apertures. It will now be seen that if the valve E be turned upon its axis in either direction the apertures formed therein will not register exactly with the corresponding apertures in the lining of the valve-casing, but will result in reducing said apertures uniformly horizontally and this without affecting the relative areas of the air and gas inlets. This is true, no matter how much the valve is turned in a direction to reduce the length of said apertures horizontally, the combined areas of the air-inlets being always eight times the combined areas of the gas-inlets. In order to secure this result, it is necessary that the air and gas apertures in the valve should be specially constructed for the purpose. I have found that if the air and gas inlets have the same vertical extent and subtend, respectively, the same angles from the axis of the valve that neither the lateral nor vertical movement of the valve will alter the predetermined ratio between the combined areas of the air-inlets and the combined areas of the gas-inlets. It will also be noted that my valve has two adjustments, the one by hand and the other by the governor, but that the adjustment of the valve in either of these ways does not change the ratio of the air and gas in the mixture.

The bottom plate or flange d^2 of the lining D is provided on its lower face with an annular recess d^5 to receive the flanged upper end of a sleeve F, said sleeve being held in place by a closing-plate A³, which extends under the flange f of the sleeve F and is provided with a central opening to fit said sleeve and a downwardly-extending split flange or ring A⁴, adapted to clamp the upper part of the sleeve F. To this end the meeting ends A⁵ of the split flange or ring are provided with a clamping-screw A⁶ for drawing the ring tightly upon the sleeve. (See Fig. 5.) The upper end of the sleeve F surrounds the lower end of the valve E, and the sleeve is provided on its inside with a projection, in this case a screw-plug f', which engages a vertically-disposed groove e⁴ in the valve, so that the valve E and sleeve F must rotate together or be jointly held against rotation while the valve E is capable of vertical movement with respect to the sleeve. The lower end of the sleeve F is preferably provided with suitable means for turning it and the valve E, consisting in this instance of a hand-wheel f². The bottom part of the valve E is provided with means for attaching it to an actuating-rod G, which is connected to the governor (not shown) of the engine, and in this instance I have shown the valve E provided with an integral plug or bottom e⁵, to which the rod

G is attached, and said plug is provided with a series of apertures e⁶ to prevent forming an air-cushion in the sleeve below the plug. 70 The rod G extends from the valve E downward through the sleeve F and through a gland F', which is screwed into a threaded portion at the lower end of the sleeve.

It will be seen that the valve E is capable 75 of movement vertically under the influence of the governor and that such movement will cause the air-inlet and gas-inlet apertures before described to be varied in size vertically, and it will also be noticed that this variation 80 of the said apertures will not affect the relation between the size of the air-inlet and gas-inlet apertures.

When the engine is running, the air will be admitted through the air-inlet apertures d^3 and e^2 , the air passing upward between the webs e of the valve to the mixing-chamber a, and the gas or vapor will enter through the apertures d^4 e^3 and pass up the central portion of the valve to said mixing-chamber, 90 from whence the mixture will pass to one or both of the engine-cylinders, according to the position of the cut-off valve C. The quantities of air and gas or vapor admitted will be controlled by the governor in proportion to 95 the load carried by the engine, the relative quantities being fixed, as before stated, no matter what position the valve E may assume vertically under the influence of the governor. If it is desired to change the horizontal width 100 of the air and gas inlet apertures, and this may be done while the engine is running, the screw A⁶ is loosened and the sleeve F and valve E are turned on their axes until the air and gas inlet apertures are adjusted to 105 the desired sizes, which adjustment will take place, as before described, without in any way affecting the relative sizes of the air and gas inlets or the control thereof by the valve E through the influence of the governor. 110

I preferably provide a spring H, surrounding the governor-rod G between the gland F' and the bottom e⁵ of the valve, to balance (or sustain the weight) the valve, so that it will be perfectly sensitive to the movements of a 115 governor-actuated rod G.

What I claim, and desire to secure by Letters Patent, is—

1. A controlling - valve for explosive - engines comprising among its members a valve-casing having parts provided with air and gas inlet apertures, a valve within said casing movable therein revolvably and longitudinally and provided with rigidly-united parts having apertures therein adapted to register with 120 the air and gas apertures in said casing, said air and gas apertures being so constructed that the combined areas of the air-inlets bear a fixed ratio to the combined areas of the gas-inlets at all times whether the valve is 125 adjusted longitudinally or revolvably, a hand-operated adjusting mechanism connected with said valve for adjusting it in one direction and a governor connected with said valve 130

for adjusting it in the other direction, substantially as described.

2. A controlling - valve for explosive - engines, comprising among its members a valve- casing provided with an air-chamber and a gas-chamber of different diameters located one above the other, said chambers being provided with inlet-apertures, a valve having rigidly-united portions of different diameters 5 mounted in said air and gas chambers so as to revolve and move longitudinally therein and provided with apertures adapted to register with those of the said casing, said apertures being so constructed that the combined 15 areas of the air-inlets bear a fixed ratio to the combined areas of the gas-inlets at all times whether the valve is adjusted revolubly or longitudinally, a hand adjusting mechanism for adjusting the valve in one direction 20 and a governor connected with said valve for adjusting it in the other direction, substantially as described.

3. A controlling - valve for explosive - engines comprising among its members, a valve- casing provided with a mixing-chamber at its upper end and air-inlet and gas-inlet chambers of different diameters below said mixing-chamber, provided with inlet-apertures, a valve having a tubular portion engaging 25 said gas-inlet chamber and communicating directly with the mixing-chamber, and a separated tubular portion rigidly secured to said first-mentioned tubular portion, engaging the air-inlet chamber and communicating directly 30 with said mixing-chamber, said valve having apertures adapted to register with said air and gas inlet apertures of the casing, a revoluble sleeve supported at the bottom of said casing and connected to said valve for 35 joint rotation without interfering with its vertical movements, means for rigidly securing said sleeve and a governor-actuated rod extending through said sleeve and connected with said valve, substantially as described.

4. A controlling - valve for explosive - engines, comprising among its members a valve- casing provided with a mixing-chamber at its upper end, an air-inlet chamber below the mixing-chamber and a gas-inlet chamber below 40 the air-inlet chamber, a lining for said casing having a portion within said air-chamber, provided with inlet-apertures and a reduced portion within said gas-chamber provided with inlet-apertures, a vertically-movable valve within said lining provided with a central tubular portion extending from the gas-chamber directly to the mixing-chamber and provided with apertures adapted to register with the gas-inlet apertures of said lining, said valve having an integral tubular portion fitting the portion of said lining within the air-inlet chamber, and communicating directly 45 with the mixing-chamber and provided with apertures adapted to register with

the air-inlet apertures of the lining, a rotatable sleeve supported in the bottom of said casing and connected to said valve to rotate therewith but permit the vertical movements of said valve with respect thereto, a clamping-ring for said sleeve secured to said casing 50 and a governor-actuated rod extending up through said sleeve and connected to said valve, substantially as described.

5. In a controlling-valve for explosive-engines, the combination with a valve-casing 55 provided with a mixing-chamber at its upper end, a cylindrical casing below the mixing-chamber provided with air-inlet ports, and a cylindrical chamber below said air-chamber of reduced diameter, and provided with gas- 60 inlet ports, of a vertically - movable valve having a tubular portion engaging the said smaller cylindrical chamber of the casing, provided with gas-inlet apertures adapted to register with those of the said chamber, said 65 tubular portion of the valve extending up through the air-outlet chamber and communicating directly with the mixing-chamber, said valve being also provided with a cylindrical portion located in said air-inlet chamber, surrounding said tubular portion and connected rigidly thereto, and provided with 70 apertures adapted to register with the air-inlet apertures, said cylindrical portion of the valve communicating directly with the mixing-chamber, substantially as described.

6. In a controlling-valve for explosive-engines, the combination with a valve-casing provided with a mixing-chamber at its upper end, a cylindrical casing below the mixing- 75 chamber provided with air-inlet ports, and a cylindrical chamber below said air-chamber of reduced diameter, and provided with gas- 80 inlet ports, of a vertically - movable valve having a tubular portion engaging the said smaller cylindrical chamber of the casing, provided with gas-inlet apertures adapted to register with those of the said chamber, said 85 tubular portion of the valve extending up through the air-inlet chamber and communicating directly with the mixing-chamber, said valve being also provided with a cylindrical portion located in said air-inlet chamber, surrounding said tubular portion and connected rigidly thereto, and provided with 90 apertures adapted to register with the air-inlet apertures, said cylindrical portion of the valve communicating directly with the mixing-chamber, substantially as described.

7. In a controlling-valve for explosive-engines, the combination with a valve-casing provided with a mixing-chamber at its upper end, a cylindrical casing below the mixing- 95 chamber provided with air-inlet ports, and a cylindrical chamber below said air-chamber of reduced diameter, and provided with gas- 100 inlet ports, of a vertically - movable valve having a tubular portion engaging the said smaller cylindrical chamber of the casing, provided with gas-inlet apertures adapted to register with those of the said chamber, said 105 tubular portion of the valve extending up through the air-inlet chamber and communicating directly with the mixing-chamber, said valve being also provided with a cylindrical portion located in said air-inlet chamber, surrounding said tubular portion and connected rigidly thereto, and provided with 110 apertures adapted to register with the air-inlet apertures, said cylindrical portion of the valve communicating directly with the mixing-chamber, and a governor connected to 115 said vertically-movable valve, substantially as described.

In testimony whereof I affix my signature in the presence of two witnesses.

JESSE WALRATH.
